INSERT FOR THE BOTTOM OF A BASKET

Harry L. Rownd, Latta, and William E. Wallace and
Thompson J. Rownd, Dillon, S.C., assignors to Rownd
& Sons, Inc., Dillon, S.C.

Filed Dec. 5, 1974, Ser. No. 529,684

Term of patent 14 years

Int. Cl. D9—04

U.S. Cl. D9—253

Fig. 3.

Fig. 4.

Fig. 5.

Fig. 6.

FIG. 1 is a top plan view of an insert for the bottom of a basket showing our new design;
 FIG. 2 is a bottom plan view thereof;
 FIG. 3 is a side elevational view thereof;
 FIG. 4 is an end elevational view thereof;
 FIG. 5 is a sectional view taken generally along line 5-5 in FIG. 1; and
 FIG. 6 is a sectional view taken generally along line 6-6 in FIG. 1.

We claim:
 The ornamental design for an insert for the bottom of a basket, as shown.
